UNITED STATES PATENT OFFICE.

CHARLES J. REED, OF GRAND RAPIDS, MICHIGAN, ASSIGNOR TO HIMSELF, GAIUS W. PERKINS, T. S. WHITE, AND THOMAS FRIANT, OF SAME PLACE.

DESIGN FOR A CASING FOR MUSICAL INSTRUMENTS.

SPECIFICATION forming part of Design No. 29,822, dated December 20, 1898.

Application filed September 29, 1898. Serial No. 692,231. Term of patent 14 years.

To all whom it may concern:

Be it known that I, CHARLES J. REED, a citizen of the United States, residing at Grand Rapids, in the county of Kent, in the State of Michigan, have invented and produced a new and original Design for a Casing for Musical Instruments, of which the following is a specification, reference being had to the accompanying drawings, forming a part thereof.

In the drawings, Figure 1 is a front elevation. Fig. 2 is an end view. Fig. 3 is a plan view, and Fig. 4 is a bottom view.

The leading feature of the design is in the outline or configuration of the casing. This consists, as shown in the drawings, of a plain top panel A, with rounded portions B extending from the top panel to the side strips C, these latter being vertically arranged and projecting slightly at each end of the casing.

The end walls of the casing are plain and support three disks, the center disk being of

smaller size than the two outside disks. These disks are shown at a b b. A band E extends across the end of the casing between the side strips and outside of the disks. A projection c of angular shape extends from one end of each of the curved panels B. The casing is symmetrical at each end, except that the disk a at one end has a broken-away part, leaving an opening. The bottom of the casing has a plain central panel, with slightly inclined side panels extending to the sides of the case.

I claim—

The design for a casing for musical instruments herein shown and described. 35

In testimony whereof I affix my signature in presence of two witnesses.

CHAS. J. REED.
